(57) **CLAIM**

The ornamental design for a vehicle steering wheel, as shown and described.

DESCRIPTION

FIG. 1 is a front, top, right side perspective view of a vehicle steering wheel showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Shading is used to illustrate the curvature of the part and not color. The claimed design is indicated by the relatively dark portions in the drawings, while the relatively light portions form no part of the claimed design. Areas surrounded by dashed broken lines and shown in half-tone shading form no part of the claimed design.
